BUILDING MATERIAL

Swan Swanson, Sparta, Mich.

Application June 29, 1935, Serial No. 29,138

3 Claims.

(Cl. 20—4)

The invention has relation to building material for the side walls of a house, and also to a frameless house, having for an object to reduce costs of manufacture and assembly. Another object is to provide a frameless house the erection of which will be facilitated. Other objects and advantages will appear hereinafter.

The invention consists in the novel construction and combinations of parts as set forth in the appended claims.

In the accompanying drawing illustrating certain embodiments of the invention,

Figure 1 is a perspective view of the invention, partly in section and broken away.

Figure 2 is a side view of the invention from the inner side, and partly broken away.

Figure 3 is a perspective view of a modification, partly in section and broken away.

Figure 4 is a similar view of another modification.

In the drawing, the numeral 1, designates longitudinal units, each centrally hollowed out from one side to provide an air space 2 and an open side 3, said units being squared off at top and bottom at 4, and including spaced horizontal upper and lower portions 5 and 6, provided with inner opposite grooves 7.

Planular vertical insert units 8, are engaged with the inner opposite grooves 7, of each longitudinal building unit 1, and serve to close in the air space thereof and to brace the upper and lower horizontal spaced portions 5 and 6 apart.

In the erection of a frameless house, spaced vertical steel rods 9, are secured at their lower ends in a suitable base or foundation, the upper and lower spaced portions 5 and 6 of the longitudinal building units being provided with perforations with which said steel rods are engaged as said building units are piled upon one another to form the side walls of the house. Said side walls being completed and suitably joined at the corners, the upper ends of said steel rods are secured together by suitable means to hold the assembly together, after which the roof is placed in position.

In Figure 1 of the drawing, the longitudinal building units are shown as half logs, formed of entire logs centrally and longitudinally divided through the hearts thereof, and the insert units are shown as of wall board, such as ply wood, the vertical inner faces of the upper and lower spaced portions 5 and 6 of the building units together with said insert units, forming a paneled interior wall. Felt strips 10 are located between

the half logs as the wall is erected to keep out air and moisture.

In Figure 4, of the drawing, the longitudinal building units 1 are exteriorly finished to simulate the ordinary siding of a frame house, being provided with tongue and groove joints 11 to keep out air and moisture and help maintain alignment, and the insert units 8 project inwardly beyond the vertical inner faces of the upper and lower spaced portions 5 and 6. Said insert units are shown as adapted for the application of expanded metal lath 12, and the recesses 13 afforded enable plaster applied over said expanded metal to lock in behind the same.

In Figure 3, of the drawing, the longitudinal building units 1 are finished exteriorly with vertical faces in the same plane.

A house trailer for a motor car has been built in accord with the invention and reduces the weight to nearly half of any other such trailer on the market, at the same time giving a stronger construction.

In some instances small or lodge pole timber may be used to advantage, such timber being of little value for square timber owing to its small size. A rustic exterior and finished interior is also provided to advantage by the use of this invention.

I claim:—

1. Building material, comprising longitudinal units squared off at top and bottom and each centrally hollowed out from one side to provide an air space and an open side and including spaced upper and lower portions having inner opposite grooves, and planular vertical insert units engaging said grooves, bracing said upper and lower spaced portions apart and closing in said air spaces, said longitudinal units being adapted to be piled upon one another to form the side wall of a house.

2. In a frameless house, a base member or foundation, spaced vertical steel rods secured at their lower ends in said foundation, longitudinal units squared off at top and bottom and each centrally hollowed out from one side to provide an air space and an open side and including spaced upper and lower portions having inner opposite grooves, planular vertical insert units engaging said grooves, bracing said upper and lower spaced portions apart and closing in said air spaces, said longitudinal units having spaced perforations with which said steel rods are engaged as they are piled upon one another to form the side walls of the house, and means engaging

the upper ends of said steel rods to hold the assembly together.

3. Building material, comprising longitudinal units, squared off at top and bottom and each centrally hollowed out from one side to provide an air space and an open side and including spaced upper and lower portions having inner opposite grooves, and planular vertical insert units engaging said grooves, bracing said upper

and lower spaced portions apart and closing in said air spaces, said longitudinal units being adapted to be piled upon one another to form the side walls of a house, the vertical inner faces of said upper and lower spaced portions and of said insert units being so related as to give a paneled effect and provide recesses. 5
